UNITED STATES PATENT OFFICE.

ERICH ARENDT, OF SAARBRUCKEN, GERMANY, ASSIGNOR TO EHRHARDT & SEHMER AKTIENGESELLSCHAFT, OF SAARBRUCKEN, GERMANY, A CORPORATION OF GERMANY.

GAS ENGINE COMBINED WITH A SCAVENGING PUMP.

Application filed March 9, 1925. Serial No. 14,251.

To all whom it may concern:

Be it known that I, ERICH ARENDT, a citizen of Germany, residing at Saarbrucken, in the State of Saargebiet, Germany, have invented certain new and useful Improvements in Gas Engines Combined with Scavenging Pumps; and I do hereby declare the following to be a full, clear, and exact description of the invention, such as will enable others skilled in the art to which it appertains, to make and use the same.

This invention relates to the combination of a gas engine with a pump for scavenging and charging purposes, the piston of the pump being mounted on the piston rod of the rearmost gas engine cylinder. A known feature in machines of this kind consists in arranging the scavenging pump piston so that it supports the rear end of the piston rod. A great disadvantage of this arrangement in practice is however that, in consequence of the copious lubrication required for the rubbing surface of the scavenging pump piston, a large amount of oil is carried by the scavenging air into the power cylinder of the gas engine and there produces undesirable effects.

Hence it has been found necessary in the operation of such machines to lubricate the scavenging pump piston as little as possible.

The object of the present invention is to meet these requirements and this is accomplished by arranging the scavenging pump piston on the piston rod so that it is practically held suspended in the scavenging pump cylinder, the piston rod itself being supported by a supplemental bearing which is located between the scavenging pump and gas engine cylinder, which bearing is movable and adjustable on a slide bed or the like to a position away from the gas-engine cylinder.

By this arrangement the desired shortness of the machine is maintained, because the piston support can easily be placed between the scavenging pump and gas engine cylinders without taking up much space.

By this arrangement it is furthermore rendered possible in almost all cases to add a scavenging pump to an existing machine.

When the adjacent stuffing box of the gas engine cylinder has to be removed it is necessary to shift this supplemental piston rod

support. To enable the stuffing box to be conveniently inspected and easily removed without employing special devices for supporting the piston rod the said piston rod support is arranged, as stated, so that it can be shifted on a slidebed in the longitudinal direction of the piston. The machining operations in the workshop and the assembling of the machine are rendered as cheap and convenient as possible by supporting the pump cylinder in a curved bed shaped in the form of a section of a cylinder that is concentric to the longitudinal axis of the machine. In accordance with the invention the piston rod support or bearing is bedded and fixed in a prolonged section of this curved bed. By this arrangement it is possible to shift both the scavenging pump cylinder and the piston rod support along the same surface or slidebed when the stuffing box of the gas engine cylinder is to be made accessible.

In the preferred embodiment of the invention, the piston rod support or bearing may be directly attached to the scavenging pump cylinder or its cover. In this construction the supplemental piston rod support and the pump cylinder are moved when the scavenging pump cylinder is shifted.

To enable the scavenging pump cylinder and the piston rod support connected therewith to be thus shifted in a most convenient manner the piston rod and scavenging pump cylinder are arranged to be temporarily but rigidly connected to each other by a screw coupling member or the like, so that the pump cylinder and the piston rod support connected therewith can be conveniently shifted through the medium of the gas engine piston rod by means of the usual flywheel stepping (starting) mechanism, i. e., the lever and pawl arrangement that operates with ratchet teeth on the flywheel.

The invention is shown by way of example in the drawing in which—

Fig. 1 is a longitudinal section of a part of the gas engine cylinder with my improved scavenging pump attached to the end thereof.

Fig. 2 is a similar view showing a modification in which the piston support or bearing is directly attached to a cylinder cover of the scavenging pump.

Fig. 3. is the cross section through a scavenging pump cylinder. In the type of machine shown in Fig. 1 the supplemental piston support *d* has the form of a pedestal which is located in the space between the pump and engine. *a* is the rear portion of a gas engine cylinder and *c* is the scavenging pump cylinder. The piston rod *g* supported by the bearing *d* passes through a stuffing box *e* in the cylinder cover of the gas engine and at its rear or free end it carries the scavenging pump piston *h*. In a machine in which the piston rod bearing *d* is arranged to be shifted lengthwise so as to provide for an easy access to the stuffing box, the scavenging pump cylinder *c* is also arranged to be shifted lengthwise. To this end there is provided a common guide surface or bed *f*, (Fig. 3). The piston rod support or bearing *d* may be directly connected to the scavenging pump as shown in Fig. 2, in which it is attached to the cylinder cover, the scavenging pump cylinder being arranged to be shifted in a guide or slide bed *f* so as to make the stuffing box *i* easily accessible. The piston rod support *d* is arranged to take the entire weight of the scavenging pump piston *h*, i. e. it holds it practically suspended in the pump cylinder *c* so that it does not touch its wall, friction with this wall arising only through the piston packing ring.

To enable the pump cylinder *c* and the piston rod support *d* to be shifted on their bed in the most convenient manner a screw coupling member *k* may be provided for effecting a rigid connection between the piston rod *g* and the scavenging pump cylinder *c*. When such rigid coupling is effected, as shown in Fig. 2, and the pump cylinder is unscrewed, i. e., loosened from the slidebed base, the bearing *d* and pump cylinder *c* can be conveniently shifted as a unit in any suitable manner, away from the adjacent end of the gas engine cylinder, thereby rendering it convenient to get access to the stuffing-box thereof. As a simple means for thus sliding the pump cylinder and the piston-rod bearing away from the gas engine cylinder, I may use the well-known fly-wheel stepping (starting) mechanism heretofore referred to, as by rotating the crank-shaft of the engine, the piston-rod will be thrust forward toward the outer end of the pump cylinder, carrying with it the pump cylinder and its attached bearing *d*.

While specific forms of the invention are illustrated in the drawings and described hereinbefore it is obvious that many changes may be made without departing from the scope and spirit of the invention.

I claim:

1. In a gas engine combined with a scavenging pump, an engine cylinder, a pump

cylinder, a piston rod extending into both cylinders, a pump piston which is carried and whose entire weight is substantially taken by said rod, and a supplemental bearing which supports said rod with the piston *70* thus virtually in suspension.

2. In a gas engine combined with a scavenging pump, an engine cylinder, a pump cylinder, a piston rod extending into both cylinders, a pump piston which is carried *75* and held suspended in the pump cylinder by said rod, and a bearing between the pump and the engine cylinder which supports said rod, said bearing being movable in the direction of the axis of the engine. *80*

3. In a gas engine combined with a scavenging pump, an engine cylinder, a pump cylinder, a piston rod extending into both cylinders, a pump piston which is carried and whose entire weight is substantially *85* taken by said rod, and a bearing between the pump and the engine cylinder which supports said rod and is adjustable in the direction of movement of said piston to permit access to the adjacent stuffing-box of *90* the gas engine.

4. In a gas engine combined with a scavenging pump, an engine cylinder, a pump structure embodying a movable cylinder, a piston rod extending into both said cylinders through a cylinder cover carried by each of said cylinders, a pump piston which is carried and whose entire weight is substantially taken by said rod, and a bearing which supports said rod and is attached to *95* the pump cylinder so as to be movable therewith to a point away from the adjacent end of the engine cylinder. *100*

5. In a gas engine combined with a scavenging pump, an engine cylinder, a pump cylinder, a piston rod extending into both said cylinders through cylinder covers belonging to said cylinders, a pump piston which is carried and whose entire weight is substantially taken by said rod, and a bearing which supports said rod and is attached directly to the cover of the pump cylinder. *105* *110*

6. In a gas engine combined with a scavenging pump, an engine cylinder, a slide bed attached to the engine cylinder, a pump cylinder slidably mounted on said slide bed, a piston rod extending into both said cylinders, a pump piston which is carried and whose entire weight is substantially taken *115* by said rod, and a bearing likewise slidably mounted on said slide bed and arranged to support said rod. *120*

7. In a gas engine combined with a scavenging pump, an engine cylinder, a slide bed attached to said engine cylinder, a pump cylinder slidably mounted on said slide bed, a piston rod extending into both said cylinders, a pump piston which is carried and whose entire weight is substantially taken *125* by said rod, and a bearing which supports said rod with the piston *130* thus virtually in suspension.

by said rod, a bearing likewise adjustably mounted on said slide bed and arranged to support said rod, and a connecting member adapted to rigidly connect the pump piston ⁵ with the pump cylinder, so that axial movement of the piston-rod will move the pump cylinder and said connected bearing.

In testimony whereof I affix my signature in presence of two witnesses.

ERICH ARENDT.
